Primary Examiner — Rosemary K Tarcza*Assistant Examiner* — Nathaniel D. Buckner(74) *Attorney, Agent, or Firm* — McKay & Associates, P.C.(57) **CLAIM**

The ornamental design for a mobile device charging stand, as shown and described.

DESCRIPTION

FIG. 1 is a perspective view of a mobile device charging stand showing our new design;

FIG. 2 is a top plan view thereof;

FIG. 3 is a bottom plan view thereof;

FIG. 4 is a rear elevation view thereof;

FIG. 5 is a front elevation view thereof;

FIG. 6 is a left side view thereof; and,

FIG. 7 is a right side view thereof.

1 Claim, 5 Drawing Sheets(56)
